UNITED STATES PATENT OFFICE.

THOMAS MICHAEL HAUGH, LE ROY CRIS SCHILLING, AND JOHN WESLEY FINCH, OF NEW BRITAIN, CONNECTICUT, ASSIGNEES TO THE EASTERN MALLEABLE IRON COMPANY, OF NEW BRITAIN, CONNECTICUT, A CORPORATION.

AUTOMATIC POKER.

1,422,442.

Specification of Letters Patent. Patented July 11, 1922.

Application filed January 14, 1918. Serial No. 211,855.

To all whom it may concern:

Be it known that we, THOMAS MICHAEL HAUGH, LE ROY CRIS SCHILLING, and JOHN WESLEY FINCH, citizens of the United States, residing at New Britain, in the county of Hartford and State of Connecticut, have invented certain new and useful Improvements in Automatic Pokers, of which the following is a specification.

10 Our invention relates to improvements in automatic pokers, and the object of our improvement is to produce a poker for use in melting furnaces in foundries and that is adapted to be maintained continuously in 15 operation and is mechanically operated.

In the accompanying drawing:—

Figure 1 is a side elevation of our improved automatic poker and a part of a melting furnace in which the poker proper is 20 operated.

Figure 2 is a plan view of the same.

Figure 3 is a side elevation of the same as viewed from the opposite side from that shown in Fig. 1.

25 Figure 4 is an end elevation of the operating mechanism.

Figure 5 is a fragmentary view on an enlarged scale of certain parts shown in Fig. 3.

30 Figure 6 is a similar view of the transverse feeding mechanism shown in Fig. 4.

Figure 7 (Sheet 3) is a sectional view on the line 7—7 of Figure 6.

Figure 8 is an end face view of the cross-connecting member of the poker.

35 Figure 9 is a plan view of the same.

Figure 10 is a sectional view on the line 10—10 of Figure 8.

Our improved automatic poker comprises a frame 10 of skeleton form for being supported from the ceiling 11 of a foundry, being positioned immediately in front of the furnace 12, and mechanism operatively housed in the said frame 10 for operating a poker 13. The poker 13 is positioned generally horizontally and extends through the mouth or fuel supply opening 14, resting on the sill 15, so that the end portion 16 is positioned within the interior portion 17 of the furnace 12, so as to be operative to contact

50 with the fuel and operate upon the same generally after the manner of a hand operated poker by reason of such movements as are imparted to the poker 13 after the manner to be described.

Such movements comprise a longitudinal 55 movement of the poker 13 so that the end portion 16 is moved back and forth over the fire and also a shifting of the poker structure transversely by a body movement, such transverse movement being effected intermittently by a relatively small shifting for each longitudinal stroke, so that the poker arms 18 travel from one side to the other along the sill 15, and the end portion 16 operates on different lateral portions of the 65 fire.

The poker 13 is water cooled, there being two arms 18 made of iron pipe, the rear ends being connected to suitable lengths of hose 19, one serving as the inlet and the other as 70 the outlet, the forward ends being connected by the end portion 16 that is in the form of a head and has an interior channel 20 for cross-connecting the pipes 18.

The pipes 18 are in spaced relation and 75 parallel, the rear end portions being rigidly secured in any suitable manner to the lower end of a vertical rod 21 of rigid construction the upper end of which is carried by the operating mechanism.

As shown, the rod 21 has at the lower end a forwardly extending branch 22 formed by a right angle bend, which branch is rigidly secured in the poker frame or bracket member 23 by the transverse bolt 24 and nut 25 85 and a set of clamping plates 26. The bracket member 23 comprises on the upper side a pair of side plates 26, one on each side of the branch 22, and secured by the middle portion to the said branch by the bolt 24, and 90 the end portions of the combined side plates and branch are positioned in channels 28 in end members 29. At each end of both of the side plates 26 is a screw 30 that secures the same to the side wall of the channel 28. The 95 end members 29 extend laterally across the lower portion of the channel 28 and extend outwardly on each side an appreciable distance to provide the desired spacing for the pipes 18 and have at the ends sleeves 31 for 100 adjustably receiving the pipes 18, these being held in adjusted position by means of set-screws 32.

The rod 21 serves as the driving rod for driving the poker, the body portion thereof 105 being maintained in a substantially vertical position as it is moved about, the poker being connected to the lower end in the man-

ner described and the upper end being connected to the driving mechanism in any suitable manner. Thus the said upper end portion is engaged with two clamps in spaced relation, comprising a lower clamp 33 and an upper clamp 34, which clamps, as shown, are connected together as a unit by a vertical connecting bar 35, and the said unit is clamped by its two ends to two similar bars 36, also in spaced relation.

Thus the bars 36 serve to support the driving rod 21, and they also constitute the two slide members of a transversely sliding frame 37, being slidably engaged with suitable bearings 38. The frame 37 as a whole comprises the bars 36 as the upper and lower members, and these are cross-connected in any suitable manner, as by the connecting bar 35, already mentioned, and by additional cross-connecting means, such as the bar 39, and supported by the frame 37 is a rack 40, positioned horizontally, with the teeth on the upper side. Thus the frame 37 is adapted to move back and forth, supported by the bearings 38, and in a direction at substantially right angles to the longitudinal directional movement of the poker.

The bearings 38 are supported by the frame-work 41 of a carriage that serves as the means for effecting the longitudinal movement of the poker, being provided with a set of wheels 42 that run on two longitudinally disposed tracks 43. The tracks 43 are supported by the main frame 10.

The means for effecting the transverse movement of the sliding frame 37 comprise a relatively large gear wheel 44 for cooperating with the rack 40 and means for intermittently moving the said gear wheel 44 comprising a ratchet wheel 45, operated by a pawl 46, and connecting means comprising a crank arm 47 incorporated with the ratchet wheel 45 and a connecting rod 48 connecting the crank arm 47 with a pin 49 that serves as a crank pin for moving the gear wheel 44 and is supported thereon in any proper manner. See Fig. 6.

A holding pawl 50 prevents return or backward movement of the ratchet wheel 45. The operating pawl 46 is carried by a swinging arm 51, which arm 51 is operatively connected by means of link mechanism 52, which may be of any suitable form, to a tripping lever 53, as shown in Fig. 5. The lever 53 is supported from the carriage frame 41 by a pin 54, has one end, shown at the left in the said Fig. 5, connected to the link mechanism 52, and the other end is provided with a nose 55 for engaging with a fixed stop 56, supported on one of the tracks 43. The stop 56 is positioned so that the nose 55 engages therewith near the end of the rearward movement of the carriage 41, the link mechanism 52 and the lever 53, with its nose 55, are so constructed and arranged

that for every such rearward movement of the carriage or truck 41 the pawl 46 effects a rotative movement of the ratchet wheel 45 to the extent of one or more teeth, as may be desired, such movement being as well understood, always in one direction. The direction of movement will be clockwise for the ratchet wheel 45 with the parts in the position shown in Figs. 4 and 6, and the effect on the connecting rod 48 will be a pull for one half of such rotative movement and a push for the other half, according to the position of the crank arm 47.

Such to and fro movement of the connecting rod 48 is utilized to effect a corresponding movement of the large gear wheel 44 on its axis 57 by making the radius for the connecting pin 49 on the said large gear wheel 44 greater than the radius of the crank arm 47, which latter rotates around the center 58 of the ratchet wheel 45, and, as a further detail, positioning the connecting pin 49 on one side only of the line of movement of the connecting rod 48. As shown, the pin 49 is on the upper side of such line of movement, and the teeth at the bottom portion of the gear wheel 44 are engaged with the rack 40 so as to move the same back and forth as the gear wheel 44 is rotated, first in one direction and then in the other.

Thus the sliding frame 37 and the poker 13 carried thereby are moved intermittently in a transverse direction, such movement as a whole being for one period in one direction and for another period in the reverse direction, and such movements being effected by the ratchet wheel 45, which latter is always rotated in one direction.

The sliding frame 37 is operatively supported by the carriage or truck 41 and the latter is moved along the tracks or rails 43 so as to effect the longitudinal movement of the said sliding frame 37 and the poker 13 carried thereby in the following manner:—

A rack 59 is mounted on the truck 41, positioned longitudinally thereof, and having teeth on the upper side.

The rails 43 are located at the lower part of the frame 10 and above the truck 41 is a platform 60 that supports the mechanism for cooperating with the rack 59 for operating the truck 41. The said mechanism comprises a segmental gear 61 of relatively large size that cooperates with the rack 59 and is supported by the shaft 62, and which is provided with a radial driving arm 63 that is connected to one end of the connecting rod 64. The other end of the connecting rod 64 is connected to the crank pin 65 that is positioned on one face of the gear wheel 66, mounted on the shaft 67. The gear wheel 66 through the medium of intermediate gearing, designated by the character 68, is operated by an electric motor 69. The parts are

so constructed and arranged that as the crank pin 65 is rotated, by rotating the gear wheel 66 on which it is mounted, the segmental gear 61 is reciprocated, being rotated 5 for a period in one direction, alternating with a period in the opposite direction. As a detail in effecting this result the radial length of the driving arm 63 of the segmental gear 61 is appreciably greater than the 10 radial distance of the crank pin 65 from the axis of its shaft 67 and the connecting rod 64 and the driving arm 63 are of suitable length and so positioned that they always operate on the upper side of the axis or shaft 15 62 for the segmental gear 61. Thus as the crank pin 65 is rotated continuously in one direction by the motor a reciprocating movement of the truck along the rails is effected, which in direction and extent is such as is 20 required to give the desired longitudinal movement for the poker.

As described, means are provided for effecting a continuous movement of the poker, such movement being interrupted only at 25 the ends of the strokes for the change in direction, and the supporting means for the poker carried by the truck are shifted bodily transversely of the line of movement of the truck by a predetermined amount for each 30 complete forward and return movement of the truck. Thus the rear end of the poker is shifted, and the front end, that is in the fire, and the portion on the sill are shifted to correspond by reason of the rigid connection 35 of the poker with the supporting means, including the double arm drive for the poker, such shifting being facilitated by the detail of dragging the poker back and forth over the sill during the longitudinal movement of the poker.

Such shifting or transverse movement is continued in one direction to correspond to the extent permitted by the width of the sill and is then reversed.

45 The poker head is maintained continuously in the fire, the water circulation provided for the same permitting this to be done without damage from the heat of the fire.

The poker to which this invention applies, 50 as mentioned, is of the form that is used in melting furnaces in foundries, and is of the specific form having an extended arm device or shank portion that is provided with an operating poker head at one end, and is 55 adapted to be projected through the fuel feed opening in the side wall of the furnace so that the said head is positioned in the interior of the furnace and exposed to the fire. The device differs from the hand operated 60 device that it replaces by having the arm device or shank portion composed of two members in parallelism instead of simply a single member.

Both forms have in use a generally limited 65 longitudinal reciprocating movement.

Accordingly, the term poker used here-with has reference to a device of the specific character mentioned.

In use the head structure rides on the fuel that is being operated upon, and the said 70 head structure, through the medium of the handle structure in the form of the arm device or shank portion mentioned, is moved back and forth generally in the longitudinal direction relatively to the handle structure. 75

Generally some part of the shank portion or handle structure intermediate the head structure and the outer end will rest on and slide on the sill of the opening in the 80 side wall of the furnace.

The efficiency of the poker is enhanced by providing a movement thereof such as has been described, comprising in combination a longitudinal movement and lateral move- 85 ment.

The longitudinal movement involves a reciprocating movement of the shank portion on the sill and the lateral movement involves a shifting of the position of the shank portion on the sill laterally, back and forth, so that the shank portion slides over different parts of the sill, and the poker structure is 90 shifted bodily from side to side.

We believe that the use of mechanism for 95 automatically operating a poker such as described to be new.

The use of water circulation permits of maintaining the head structure constantly and continuously within the interior of the 100 furnace.

By providing the handle structure in the form of two parallel members, as shown, and cross-connected by the head structure, means are provided for effecting the water 105 circulation and also a poker structure is provided that is superior to the poker that it replaces in operating qualities.

Thus, the double arm form of handle structure provides superior means for guiding the head structure in a positive and effective manner, both in operations involving pulling the head structure over the fuel and in those involving pushing or thrust.

As mentioned, the rear or outer end of 115 the poker is rigidly connected to the supporting means, wherefore there is a tendency under conditions of use to positively position and guide the poker structure in a definite direction relatively to the said 120 supporting means which serves to effect the bodily shifting of the poker structure from side to side as the supporting means are shifted.

We claim as our invention:— 125

- 1: In combination in a poker structure, a rail supported truck having a limited to and fro movement, a frame operatively supported by the said truck for limited to and fro movement in the transverse direction, 130

a poker structure connected to the said frame, and tripping mechanism operative to periodically effect a movement of the said frame and poker responsive to such to and 5 fro movement of the truck.

2. In combination in a poker structure, a poker operatively supported, a motor for operating the said poker, and automatically controlled mechanism interconnecting the 10 said motor and poker for effecting a longitudinal movement of the said poker and also effecting a transverse shifting of the said poker.

3. In poker operating mechanism, a 15 truck for supporting a poker mounted on a set of rails and provided with a rack, rotatively operating gearing provided with a crank pin, a gear member cooperating with the said rack, a connecting rod connecting the 20 said crank pin and gear member, and the said gearing, connecting rod, and gear member being so constructed and arranged that rotative movement of the said crank pin will effect a reciprocating movement of the 25 said truck.

4. In poker operating mechaninsm, a truck having a reciprocating movement along a set of rails; a poker supported by the said truck through the medium of a sliding 30 frame, the said sliding frame being supported in slide bearings and having a rack, a gear member cooperating with the said rack and supported by the said truck, a ratchet wheel also supported by the said 35 truck, a connecting rod connecting the said ratchet wheel and gear member, means for intermittently imparting rotative movement to the said ratchet wheel responsive to such reciprocating movement of the truck comprising 40 a pawl for engaging with the said ratchet wheel, and the said ratchet wheel, connecting rod, and gear member being con-

structed and arranged that rotative movement of the said ratchet wheel in one direction will effect alternatively movements of 45 the said poker in opposite directions.

5. In combination, a furnace having a fuel feed opening in the side wall, a poker structure having an arm portion and a head portion at one end of the said arm portion, the said poker structure being projected through the said opening so that the said head portion is positioned within the interior of the said furnace, motor driven means for moving the said poker structure 55 back and forth longitudinally and also to shift the position thereof bodily laterally while the said head portion is being maintained so positioned within the interior of the furnace, and the said arm portion and head portion being provided with passages for water circulation so as to permit of continuous operation under conditions of combustion within the said furnace.

6. A furnace having a fuel feed opening 65 in the side wall that is provided with a sill, a poker structure projected through the said opening and having a shank portion resting on the said sill and a rear end portion extending outwardly from the said sill, supporting means connected to the said rear 70 end portion, means for guiding the said supporting means for longitudinal reciprocating movement, and the said supporting means and rear end portion being rigidly 75 connected so as to effect a positive guiding of the said poker structure.

7. A combination as described in claim 6, the said poker structure having passages for water circulation.
